(57) **CLAIM**

The ornamental design for a security plate for automotives, as shown and described.

DESCRIPTION

FIG. 1 is a front, top, and left side perspective view of an ornamental design for a security plate for automotives; FIG. 2 is a front side elevation view thereof; FIG. 3 is a right side elevation view thereof; FIG. 4 is a left side elevation view thereof; FIG. 5 is a top plan view thereof; and, FIG. 6 is a bottom plan view thereof.

The dashed broken lines in the Figures show portions of the security plate for automotives that form no part of the claimed design.
